VISIBLE CARD RECORD SYSTEM

Robert J. Copeland, Toronto, Ontario, Canada

Application March 31, 1942, Serial No. 437,003

8 Claims. (Cl. 129—16)

This invention relates to improvements in visible card record systems. Numerous systems have been devised for the keeping of accounts and records on cards and holders of various types have been used which enable the cards to be quickly scanned and from which an individual card may be selected and readily removed for additional entries or for other purposes.

The present invention has been devised particularly in connection with that type of card record where drawers, cabinets or other types of holders are provided with a plurality of parallelly arranged rods and the bottom edges of the cards are formed with a plurality of equally spaced notches to receive the rods with the cards arranged in echelon formation. In such a system groups of cards are separated by division boards or dividers and it has been the custom when it is desired to remove a group of cards from a drawer or tray, the group of cards and the divider are grasped by the upper edges and lifted. It has been found that in thus transferring groups of cards serious disarrangements may occur and if the card or a divider slips in the fingers the entire group may become completely disorganized.

The principal object of the present invention is to avoid the accidental disarrangement of cards during the handling of groups thereof and to further simplify the arrangement of the cards in the record cabinet and further, to modify the cost of the equipment.

The principal feature of the invention consists in providing the dividers for groups of cards with a trough-like bottom edge adapted to engage the bottom edges of the cards to enable their being lifted from the cabinet and further, that such trough arrangement on the divider is provided with means for engaging the notched cards to retain them in their spaced echelon arrangement.

A still further and important feature consists in the novel arrangement of notched means within the casing or holder adapted to engage the individual card-holding members in varied positions.

In the accompanying drawings

Figure 1 is a perspective view of a card holding cabinet showing the front and one end wall broken away and showing the arrangement of card-holding tray units therein.

Figure 2 is an enlarged fragmentary sectional view of the upper portion of one of the trays for holding the index card.

Figure 3 is a vertical sectional view of the hinge joint of the card holder and index member as shown in Figure 2.

Figure 4 is a vertical sectional view similar to Figure 3 showing the index member turned downwardly.

Figure 5 is an enlarged perspective fragmentary view of the lower corner portion of one of the card holders illustrated in Figure 1.

Figure 6 is an elevational detail view of a portion of a modified bottom member for one of the card holders.

Figure 7 is a perspective view of one of the card holders illustrated in Figure 1 removed from the cabinet and showing the index holder turned downwardly and a card arranged therein raised from the placing holders in the bottom.

Figure 8 is a fragmentary perspective detail looking into the inside end of a cabinet showing the arrangement of the individual card holders therein in two different positions and illustrating the means for supporting the card holders in various positions.

Figure 9 is an enlarged fragmentary perspective detail of a portion of one of the card holders showing the arrangement of an intermediate end supporting member.

Figure 10 is a vertical sectional elevation of a portion of the end of one of the card holding members as illustrated in Figure 8 showing the upper pivotal pin support.

Figure 11 shows a modified form of card holder. It has been found that with visible card record systems where the cards are placed in echelon arrangement it is somewhat difficult for the operator to read items entered on the card close to the bottom thereof and the present invention has been devised to enable the person examining the card to lift a definite group of cards for close examination. This is accomplished in a very simple manner by providing the bottom edge of the separating board with a trough-like construction which will extend under the bottom edges of the cards so that when the board is lifted out the cards will not require to be held but will rest in the trough-like structure.

In the preferred form of this invention the cabinet structure is simplified by dispensing with the spacing rods and each of the group-separating boards is formed to comprise an individual tray 8 to receive and hold a series of cards 9.

In the preferred form of construction of the trays 8, the back board, which is of rectangular form and of dimensions to fit loosely between the ends of the cabinet 10, is fabricated from a plurality of sheets of metal, cardboard or thin vulcanized fibre.

As illustrated in detail in Figure 5 the outer

sheet 11 extends past the bottom edges of the sheets 12 and 13 and this single thickness of the fibre is bent around a preformed trough-shaped strip of metal 14, the outer edge of which is formed with a return bend 15 which grips the edge of the fibre sheet.

Placed in the bottom of this U-shaped metal trough is a half round bar 16, which may be soldered or spot-welded in place, and mounted on the top flat surface of the bar 16 at spaced intervals are a plurality of inverted U-shaped members 17 preferably formed of sheet metal with out-turned lug ends which are soldered, riveted or spot-welded to the flat face of the bar 16.

The members 17 are spaced apart to fit into the notches between the lugs 5 of the cards 6, and while these members may be placed in position into each of the notches of a card they may be spaced apart every three or four notches, as illustrated clearly in Figures 1, 5 and 7. If it is desired to have these members arranged in every notch a long, thin strip of metal may be formed up to the shape illustrated in Figure 6 where the strips 18 constitute a plurality of equally spaced lug members separated by straight lengths of metal and the whole may be secured to the bottom bar 16.

The bar 16 extends beyond the end of the trough-shape member 14 and the cabinet is provided with a notched bar 19 arranged at the bottom and extending from front to back and the tray members when inserted into the cabinet will be spaced apart and held in their respective spaced positions by the extending ends 20 of the bars 16 resting in the notches of the members 19. The rounded under side surfaces of the bars 16 form a rocking support for the trays.

It will be readily understood that cards such as used in previously known systems may be arranged in the trays in echelon arrangement and the trays may be swung to a backwardly slanting position, as illustrated in Figure 1, while other trays forward of them may be swung forwardly to allow the operator to examine the record on the card, but if the operator cannot see the items on the card clearly he may of course remove the card if only one card is being examined, but he may lift the tray with its complement of cards out of the cabinet without disturbing any of the other trays and the cards will be held securely in the tray from disarrangement.

It is found desirable to provide means for supporting the tray in a raised position without removing it from the cabinet and this may be accomplished in different ways.

In Figure 8 I have illustrated the inside of a side of a cabinet showing one tray resting in the notched bottom end supports 19. Slightly over mid-way of the height of the cabinet I have arranged a bar 21 which is shown provided with an inwardly and upwardly turned flange 22 formed with open notches 23. This turned flange is preferably arranged in sections with gaps or spaces 24 therebetween to permit the end extensions 20 of the bottom bars to pass upwardly freely, and also to permit the passage of lug extensions 25 which are arranged intermediate of the height of the trays and extending from the ends thereof.

One of these extension lugs 25 is illustrated in detail in Figure 9. It is formed of a piece of flat sheet metal having a lug extension which is preferably turned upwardly into U-shape to form a

round bottom edge support 26. This is set into the end of the tray member and is preferably spot-welded or riveted to the metal end binding strip 27 which it is preferred to reinforce the trays with at the ends.

This extension lug 25 normally is arranged below the notched strip 25 when the bottom bar extensions 20 fit into the notched bars 19 at the bottom of the casing or cabinet. The tray may 10 be lifted up a short distance, the lugs 25 passing through the gaps or spaces 24 and then be hung in the notched flange of the bar 21.

I also provide a bar 28 arranged adjacent to the top edge of the cabinet which has an inward 15 and upturned flange formed with notches 29. The card-holding tray may be lifted up to the second position shown in Figure 8 so that the lug members 25 at each end rest in the notched bar 28.

20 When a tray is raised into this upper position it may be held in a slanting position while the operator is working with same by means of a hooked bar 30, which is formed with a piece of wire having a hook at each end, and which is 25 slipped under the bottom edge of the tray which is raised and the other hooked end is slipped over the top of the next forwardly adjacent tray, or the bottom may engage the bar 21.

I may provide each of the trays with secondary 30 end lug projections 31 arranged between the lugs 25 and the top of the tray a suitable distance so that the tray can be set into position with the bottom portion spaced from the bottom of the cabinet so that the end lugs 20 of the bottom bars will not engage the notched bars 19. This 35 will be found useful where a cabinet may be crowded for space, that is, where a letter or group of letters requires a secondary tray and if the cabinet is full at the bottom the next tray 40 can be inserted as there is space between the trays above the bottom trough-shaped portions.

It will be noted in reference to Figure 5 that in fabricating the back of the tray of three sheets the outer sheet 11, being bent around with the 45 metal trough-shaped member 14 and the next sheet 12 abutting the edge of the trough-shaped member, the inner sheet projects inwardly beyond the space of the trough-shaped member and overlaps the top edges of the members 17 secured to the bottom bar 16, so that when cards are 50 being placed in position there will be no tendency for them to catch between the back of the tray and the looped lug members.

It may be desirable that an index be provided 55 on each of the trays and such a device may be arranged in a very simple manner. A shallow trough-shaped member 35, having the longitudinal edges 36 turned inwardly and capable of receiving and holding the edges of index cards, is mounted on a hinge 37, one member of which is secured to the back panel of the tray.

This index member when swung upwardly in the position illustrated in Figure 1, may have the index slips 38' inserted therein to align with the index portion of the cards 9 mounted in the tray. When the tray is not in use the hinged index member may be turned downwardly to the position illustrated in Figure 7 and it may have the key index character shown on the back thereof and when the index member is turned downwardly in the position illustrated in Figure 7 it forms a holder to hold the cards in that particular tray in place so that even very unusual handling of the tray will not dislodge the 70 cards from their proper position.

It may be found desirable to dispense with this index member and a looped wire holder 38 may be hinged to the top of the tray as illustrated in Figure 11 to overlap the top edges of the cards spaced in the tray and hold same securely. This open wire loop will not obscure the material printed on the cards.

The tray may be taken out or lifted into any one of the positions herein described and illustrated, particularly in Figure 8, and the index member may be turned upwardly for reference, or the index members may be turned upwardly without lifting the tray from its normal position resting in the bottom support 19.

It will be readily appreciated that visible record cards of the type described may be placed in trays and the trays may be fitted into holding cabinets of various kinds, such as desk drawers or desk-top cabinets, or other and portable types.

A device such as described is extremely simple and may be manufactured at very low cost.

Instead of fabricating the back of the tray of a plurality of sheets, as shown in Figure 5, it may be made of a single thickness of fibre and the lower edge portion may be milled down to the required thinness to lap around the trough-shaped metal reinforcement 14.

What I claim as my invention is:

1. In a visible card record system, a tray comprising a back having its lower edge bent into trough-like form, a trough-shaped reinforcing strip secured to said bent portion of the back, and a plurality of upstanding lug members secured in the bottom of said reinforcement and equally spaced adapted to engage notches in the bottom edge of the record cards.

2. In a visible card record system, a tray having a trough-shaped bottom adapted to receive and hold a group of cards, cards arranged with their bottom edges within said trough-shaped bottom, means in the trough-shaped bottom for spacing said cards in overlapping endwise arrangement, and an index holder hinged to the top of said tray adapted to be swung downwardly to engage and hold the overlapped record cards within the tray.

3. In a visible card record system, a tray hav-

ing a trough-shaped bottom adapted to receive and hold a group of cards, means in the trough-shaped bottom for spacing said cards in overlapping endwise arrangement, and an index holder hinged to the top of said tray adapted to hold index cards aligned with the overlapped record cards within the tray.

4. A tray for holding record cards comprising a flat back having its bottom edge bent into a trough shape, a trough-shaped metal reinforcement secured in the trough of said back, a half round bar secured in the bottom of said trough, and a plurality of lugs formed of U-shaped metal strips having their ends secured to the upper edge of said half round bar, said lugs being equally spaced apart and adapted to effect the endwise spacing of the record cards in said tray.

5. A tray as claimed in claim 1 in which a reinforcing bar is arranged in the trough-shaped strip and the lug members arranged in the bottom of the reinforcement comprising inverted U-shaped members having out-turned ends secured to the reinforcement.

6. A tray as claimed in claim 1 in which the trough-shaped reinforcing strip is arranged within the trough-shape bend of the back and has a return bent edge embracing the edge of the trough-shaped portion of said back.

7. A tray as claimed in claim 1 in which a half round bar is secured in the bottom of said reinforcing strip and the ends thereof extend beyond the tray and present bearing supports therefor, and a cabinet having notched bars at the bottom adapted to engage the extending ends of the bar extensions from said tray.

8. In a visible card record system, a cabinet having notched bars arranged at the bottom and intermediate of the height of its sides, trays having trough-shaped bottoms to hold a group of record cards, lugs spaced within said trough-shaped tray bottoms to space the record cards therein, and means extending from the sides of said trays adapted for engagement in the notched bars at the sides of the cabinet to hold said trays in relative spaced arrangement.

ROBERT J. COPELAND.
